Primary Examiner — Selina Sikder(74) *Attorney, Agent, or Firm* — Crestron Electronics, Inc.(57) **CLAIM**

The ornamental design for a wall mounted button panel, as shown and described.

DESCRIPTION

FIG. 1 shows a top-front perspective view of a wall mounted button panel.

FIG. 2 shows a bottom-front perspective view of the wall mounted button panel.

FIG. 3 shows a front elevation view of the wall mounted button panel.

FIG. 4 shows a left side view of the wall mounted button panel.

FIG. 5 shows a right side view of the wall mounted button panel.

FIG. 6 shows a top view of the wall mounted button panel; and,

FIG. 7 shows a bottom view of the wall mounted button panel.

The broken line portion of the figure drawings is included to show unclaimed subject matter only and forms no part of the claimed design.
